CLAIM

The ornamental design for a combined platform truck and hand truck dolly, as shown and described.

DESCRIPTION

FIG. 1 is a top plan view of a combined platform truck and hand truck dolly showing my new design;

FIG. 2 is a front elevational view thereof;

FIG. 3 is a side elevational view thereof with the opposite side thereof being identical;

FIG. 4 is a bottom plan view thereof;

FIG. 5 is a rear elevational view thereof;

FIG. 6 is a perspective view thereof, in an alternate position for use as a container platform truck;

FIG. 7 is a perspective view thereof, in another alternate position for use as a hand truck dolly.

FIG. 1.

FIG. 2.

FIG. 3.

FIG. 4.

FIG. 6.

FIG. 5.

FIG. 7.
